UNITED STATES PATENT OFFICE.

JOHN MACCORMACK, OF BAYONNE, NEW JERSEY, ASSIGNOR TO ROYAL C. PEABODY, OF BROOKLYN, NEW YORK.

AUTOMATIC STOKER FOR MINE REFUSE OR OTHER VERY FINE FUEL.

SPECIFICATION forming part of Letters Patent No. 715,826, dated December 16, 1902.

Application filed September 12, 1901. Serial No. 75,169. (No model.)

To all whom it may concern:

Be it known that I, JOHN MACCORMACK, a citizen of the United States, residing at Bayonne, in the county of Hudson and State 5 of New Jersey, have invented a certain new and useful Improvement in Automatic Stokers for Mine Refuse or other Very Fine Fuel, of which the following is a description.

My invention relates to improvements in 10 automatic stokers for use with very fine fuel, such as mine refuse.

In my Patent No. 679,275, dated July 23, 1901, I describe and claim improvements in automatic stoking mechanism wherein is used 15 a magazine having flaring upper walls surmounted by twyer-blocks and containing a vertically-reciprocating platen, to which fuel is continuously supplied from a feeding-tunnel, the grate-bars being arranged in two 20 banks on both sides of the magazine. In operation the platen elevates the fuel, causing it to pile over the twyer-blocks and spread out upon the grate-bars. On the return downward stroke of the platen the fuel within the 25 upper portion of the magazine bridges over between the flaring walls thereof, so as not to follow the platen to the bottom of its downward stroke. With mine refuse and other very fine fuel it is desirable that independent 30 means should be interposed in the magazine for blocking the fuel in the upper portion thereof and preventing it from merely moving up and down with the platen. My present application provides a device for this purpose and makes the stoker especially applicable for use with such fine fuel.

In order that the invention may be better understood, attention is directed to the accompanying drawings, forming part of this 40 specification, and in which—

Figure 1 is a cross-sectional view of a furnace equipped with my present improvements; Fig. 2, a section on the line 2 2 of Fig. 1, and Fig. 3 a detailed perspective view showing one pair of movable gates.

In all of the above views corresponding parts are represented by the same numerals of reference.

1 1 are the side walls of the furnace, 2 the 50 front wall thereof, and 3 the bridge-wall, all constructed as heretofore.

4 4' are twyer-blocks carried on the front and bridge walls, respectively, of the furnace, and 5 5 are corresponding twyer-blocks, preferably embedded in the side walls of the furnace, as shown, and which may connect with the twyer-blocks 4 4'. All of these blocks are made, preferably, in sections, as is common, in order that they may be removed or interchanged when desired. The blocks 4 4' are 60 carried on angles 6, as shown. Mounted in suitable bearings in the blocks 4 4' are the grate-bars 7, each preferably formed of a series of sections of cast-iron, though obviously other materials may be used. The grate-bars 65 are carried on shafts 9, rounded at the ends to take into bearings in the twyers 4 4'. I illustrate the grate-bars as being arranged in two sets, inclining slightly away from a central magazine 12, located at the center of the 70 ash-pit, whereby material introduced vertically upward through the magazine will be distributed equally to the two sets of grate-bars and by the latter will be fed uniformly over their entire area, as will be 75 explained. Mounted to reciprocate in the magazine is a platen or platform 13, the latter being reciprocated vertically, as I describe in my said patent, from a lever connected with an eccentric 13' on a power-driven shaft 14. 80 Mounted on said shaft is a feed-worm 14', by means of which the fuel is supplied from a hopper 15 to the magazine above the platform 13. The hollow grate-bars 7, immediately adjacent to the magazine, constitute rotating 85 twyers, and each of these bars is mounted above the hollow walls 16 of the magazine, which walls are supplied with air under pressure through pipes 17, whereby the air will be blown through the rotating twyers, so that 90 the latter will be kept entirely cool and will properly supply the necessary oxygen for combustion. At its end the magazine 12 is provided with ordinary stationary twyer-blocks 18, as shown. If desired, a low-pressure pipe 19 may be located in the ash-pit on either side of the magazine to supply air below the grate-bars when a forced draft is desired. At the outside of each grate-section 95 I provide a clinker-receiving apron 20, onto which the clinkers from the grate-sections are deposited. Each apron is supported on 100

a series of arms 21, keyed to a rock-shaft 22, which extends through the front wall 2, so as to be operative from the outside when it is desired to dump the clinkers from the aprons

5 20. The rotating grate-bars 7 are rotated in the same direction by any suitable mechanism for the purpose. In the drawings I illustrate a toothed bar 23, mounted beneath the grate-bars of each set near the front of the furnace. This toothed bar at its inner end is carried on a lever 24, pivoted in a bracket at the side of the magazine, and at its other end the toothed bar is connected to an eccentric 26 on a shaft 27. The teeth of the toothed bar 23 are so disposed as to engage with the slots or openings 11 in the several grate-bars, or, if desired, said grate-bars may be formed with special openings therein for the engagement of said teeth therewith. Each shaft is 15 20 rotated in any suitable way.

It will be obvious that as either shaft 27 is rotated in the direction of the arrow the elevation of the pivot connection with the toothed bar 23 above the horizontal plane of said shaft 25 will engage the feed-bar with the several grate-bars, which devices will then be rotated to a slight extent. As the connection with the toothed bar passes below the horizontal plane of the shaft 27 the toothed bar will be 30 withdrawn downwardly from engagement with the rotating devices, so that the latter will remain stationary. Thus an intermittent feed movement will be given to the twyers and grate-bars to slowly advance the fuel fed 35 from the magazine to the grate-sections toward the side walls of the furnace, whereby the clinker will be fed from the grate-sections and will accumulate on the aprons 20, which can be dumped from time to time from the 40 outside.

With my present improvement I make use, preferably, of a pair of gates 30, which are pivoted in recesses in the inner walls of the magazine. Obviously instead of two opposing gates only a single gate may be employed, extending across the magazine and pivoted at one side. The gates, as shown in Fig. 3, are made, preferably, in sections strung on the pivot-rod 31 and provided with slots or perforations 32 therein to permit any gases to 45 pass up through the gates, and thereby prevent the possibility of explosion within the magazine. The platform 13 is also provided at its sides with rollers 33, which closely engage the side walls of the magazine, so that as the platform is elevated such rollers will 50 engage the gates 30 to completely open the same, permitting the charge of fuel on the magazine to be elevated up through the magazine and be forced out upon the grate-surfaces. As the platform 13 descends in its 55 movement the gates 30 will obviously close 60

by their weight, so that the fuel, however fine it may be, will be prevented from following the platform to its downward limit. It will 65 be observed that the gates in opening will move upwardly and outwardly from each other, following the dotted lines shown, so as to tend to break up any clinkered material which may accumulate in their path. 70

Having now described my invention, what I claim as new, and desire to secure by Letters Patent, is as follows:

1. In an automatic stoker, the combination with a magazine and grate-bars arranged near the upper end thereof, of a vertically-movable platform in the magazine, means for supplying fine fuel to said platform, and a pivoted gate in the magazine arranged to open upwardly to permit the passage of fuel elevated 75 by said platform, substantially as and for the purposes set forth.

2. In an automatic stoker, the combination with a magazine and grate-bars arranged near the upper end thereof, of a vertically-movable 80 platform in the magazine, means for supplying fine fuel to said platform, and a pivoted slotted gate in the magazine arranged to open upwardly to permit the passage of fuel elevated by said platform, substantially as and 85 for the purposes set forth.

3. In an automatic stoker, the combination with a magazine and grate-bars arranged near the upper end thereof, of a vertically-movable 90 platform in the magazine, means for supplying fine fuel to said platform, and a pivoted slotted sectional gate in the magazine arranged to open upwardly to permit the passage of fuel elevated by said platform, substantially as and 95 for the purposes set forth. 100

4. In an automatic stoker, the combination with a magazine and grate-bars arranged near the upper end thereof, of a vertically-movable platform in the magazine, means for supplying fine fuel to the platform, and a pair of pivoted gates in the magazine arranged to open upwardly and outwardly to permit the passage of fuel elevated by said platform, substantially as and for the purposes set forth. 105

5. In an automatic stoker, the combination with a magazine and grate-bars arranged near the upper end thereof, of a vertically-movable platform in the magazine, means for supplying fine fuel to the platform, and a pair of pivoted sectional gates in the magazine arranged 110 to open upwardly and outwardly to permit the passage of fuel elevated by said platform, substantially as and for the purposes set forth. 115

This specification signed and witnessed this 6th day of August, 1901.

JOHN MACCORMACK.
